UNITED STATES PATENT OFFICE

PATRICK P. CUNNINGHAM, OF PROVO, UTAH

TUYÈRE

Application filed March 23, 1932. Serial No. 600,803.

This invention relates to improvements in blast furnace tuyères and contemplates the provision of a new type of tuyère having means incorporated therein or associated therewith for directing a scavenging current of air to the interior of the tuyère so as to blow away any molten iron or molten slag or cinder which may tend to run back on or be precipitated in the tuyère opening when the main air blast is interrupted or diminished, when checking the furnace. The invention will be fully apparent from the following specification when read in connection with the accompanying drawing and the features of novelty will be defined with particularity in the appended claims.

In the drawing—

Fig. 1 is a vertical longitudinal section of the lower portion of a blast furnace showing a tuyère and related equipment embodying my invention;

Fig. 2 is a face view of my improved tuyère;

Fig. 3 is a longitudinal section thereof on line 3—3 of Fig. 2.

Referring in detail to the drawing, 10 represents a typical form of blast furnace having the usual hearth section 12, bosh 14 and stack wall section 16. Surrounding the furnace, there is the usual bustle pipe 18, which supplies a high pressure air blast to a plurality of so-called blowstocks 20, which are connected with the blow pipes 22 and the tuyères, indicated as a whole at 23. Each tuyère 23 is tapered as shown and is removably held in the central tapered opening of the usual water cooled tuyère cooler 25. In the usual form of tuyère, there is a tendency to destroy the tuyère when molten iron or slag flows into the blast opening thereof.

Various expedients have been suggested for cutting down the blast furnace operating expense by providing protective means usually secured either in the nose of the tuyère, or formed of refractory jackets surrounding the tuyère. These are relatively expensive adjuncts.

Instead of using such refractory protectors to prolong the tuyère life, I provide means for directing a scavenging current of

air in the tuyère opening. This scavenging current can be applied independently of the main air blast, which flows through the tuyère. This is of importance because much tuyère damage is done while the main air blast is shut off, or while the pressure of the main air blast is materially lessened. The scavenging current of air blows away any molten iron or slag which tends to accumulate and thus prevents such iron or slag from exerting a destructive or erosive action on the tuyère wall.

As illustrated best in Figs. 2 and 3, my improved tuyère has the usual central tuyère opening 24 through which the main air blast is directed by the usual blow pipe 22. A particular feature of my improved tuyère is the provision of a conduit 26 having an orifice 28 opening into the main opening 24 of the tuyère, so that a scavenging jet of air, as indicated by dotted lines at 30, may be directed against the inner wall 32, which defines the main tuyère opening. This jet of air is effective to blow out any molten cinder or molten metal which may tend to run back into the tuyère when the main blast pressure is either diminished or shut off, such as occurs when checking the furnace, or when interrupting the normal blowing pressure. The conduit 26 of each tuyère will be connected with a branch pipe 34 having a suitable two-way valve 36 therein, said branch pipe connecting with a high pressure auxiliary bustle pipe 38. This bustle pipe will be connected with a suitable source of high pressure air and will provide means whereby a high pressure stream of scavenging air can be supplied to any selected tuyère, it being understood that the supply of such scavenging jet is controlled by opening the appropriate control valve 36.

The preferred form of tuyère of my invention is proportioned approximately as shown at Fig. 3, wherein it is noted that the upper part 40 projects inwardly of the furnace a greater distance than the lower part 42. This upper inwardly extending portion serves to intercept the dripping iron from above. Also this form of tuyère is preferred because it gives a slight overhang beyond the point

where the jet from the conduit 26 strikes the surface of the wall 32. The tuyère is preferably water jacketed as shown and the conduit 26 is disposed at an angle to the longitudinal axis of the tuyère opening 24 as shown.

From the foregoing, it is apparent that my invention provides a relatively inexpensive means for scavenging the interior of the tuyère independently of the normal air blast pressure. This contributes to the useful life of the tuyère, yet does not involve the use of special protective coverings, fillings, or other changes in tuyère structure. The addition of the high pressure air supply pipe adds very little extra expense to the cost of the original installation and of course the high pressure air supply is always available around blast furnace equipment. The invention, therefore, provides means for materially cutting down the tuyère expense and it is thought that this saving in prolonging the tuyère life will more than pay for the additional cost of air supply equipment in a short period of time.

25 Various modifications may be made by those skilled in the art without departing from the invention as defined in the appended claims.

What I claim is:—

- 80 1. A tuyère having an inner wall defining the blast opening of the tuyère and means communicating with said opening for directing a scavenging current against said wall.
- 85 2. A tuyère having an inner wall defining the blast opening, other walls secured thereto constituting the water jacket for the tuyère, and a conduit formed in the tuyère body for directing a scavenging current of air into the blast opening of the tuyère.
- 90 3. A blast furnace having a plurality of tuyères, means formed in each of said tuyères for projecting a scavenging current thereto, a high pressure air supply means common to a plurality of the blast furnace tuyères and valve means for controlling the air supply to the scavenging means.
- 95 4. A blast furnace having a plurality of tuyères, each tuyère having a blast opening, means for supplying the usual air blast to the tuyères and means for supplying auxiliary scavenging high pressure air jets to the blast openings of said tuyères.
- 100 5. A tuyère of the character described having an inner annular wall defining a blast opening, and a conduit disposed obliquely to the longitudinal axis of said blast opening and air supply means communicating with said conduit.
- 105 6. A tuyère of the character described having an inner annular wall defining a blast opening, and a conduit disposed obliquely to the longitudinal axis of said blast opening and air supply means communicating with said conduit and valve means controlling the

flow from said air supply means to said conduit.

7. A blast furnace tuyère having an inner wall defining the blast opening of the tuyère, means for supplying the usual air blast to said blast opening, a conduit communicating with said blast opening and fluid pressure supply means communicating with said conduit for supplying a scavenging jet to the wall of the blast opening.

In witness whereof, I have hereunto signed my name.

PATRICK P. CUNNINGHAM.
